UNITED STATES PATENT OFFICE.

ROY W. SCHWEIKER, OF LANSDALE, PENNSYLVANIA.

DESIGN FOR A MIRROR LIGHTING FIXTURE.

Application filed December 16, 1925. Serial No. 15,770. Term of patent 14 years.

To all whom it may concern:

Be it known that I, ROY W. SCHWEIKER, a citizen of the United States, residing at Lansdale, in the county of Montgomery and State of Pennsylvania, have invented a new, original, and ornamental Design for a Mirror Lighting Fixture, of which the following is a specification, reference being had to the accompanying drawings, forming a part thereof, in which:—

I claim:

The ornamental design for a mirror lighting fixture, as shown.

In testimony whereof I affix my signature.
ROY W. SCHWEIKER.
